UNITED STATES PATENT OFFICE.

ALONZO C. CAMPBELL, OF ASHEVILLE, NORTH CAROLINA.

ACTUATING DEVICE FOR PERCUSSION-TABLES.

1,141,767.

Specification of Letters Patent.

Patented June 1, 1915.

Application filed April 22, 1914. Serial No. 833,658.

To all whom it may concern:

Be it known that I, ALONZO C. CAMPBELL, a citizen of the United States, and a resident of Asheville, in the county of Buncombe and State of North Carolina, have invented a new and Improved Actuating Device for Percussion-Tables, of which the following is a full, clear, and exact description.

10 The object of the present invention is to provide a new and improved actuating or impelling device for percussion tables, arranged to give the desired impetus to the percussion table and inertial resistance to impact with a view to facilitate the separation of the heavier and lighter materials.

15 In order to accomplish the desired result, use is made of a pan mounted to oscillate, a revoluble fly wheel provided on its peripheral face with a percussion lug or tappet adapted to engage one end of the said pan, and a spring device connected with the said pan to draw the latter toward the said fly wheel and to exert an upward and a forward pull on the pan.

20 A practical embodiment of the invention is represented in the accompanying drawings forming a part of this specification, in which similar characters of reference indicate corresponding parts in all the views.

25 Figure 1 is a side elevation of the actuating device for a percussion table, part of the pan being shown broken out and the housing and ceiling being shown in section; Fig. 2 is a plan view of the same; Fig. 3 is a reduced rear end elevation of the same, part of the pan being broken out and the ceiling of the housing being shown in section; Fig. 4 is a side elevation of a 30 modified form of the spring device, the overhead beams being shown in section; and Fig. 5 is a side elevation of the actuating device as applied to two coöperative pans receiving a percussive action from one 40 fly wheel, the floor and housing being shown in section.

45 The bottom A' of the pan A is connected by hinges B, B' with legs B², B³ connected at their lower ends by hinges B⁴, B⁵ with blocks C, C', bolted or otherwise secured to a support D, of any approved construction. The leg B² is arranged at the forward end of the pan A while the leg B³ is arranged near the rear or tail end, the leg B² being 50 somewhat longer than the leg B³.

On the block C are mounted bearings E

in which is mounted to turn a shaft F provided with a pulley F' connected by a belt with other machinery for imparting a rotary motion to the shaft F.

60

On the shaft F is secured a massive fly wheel G provided on its peripheral face with a diminutive percussion lug or tappet G' adapted to be engaged by a bumping block H secured on the forward end of the 65 keel I forming part of the pan A. In order to hold the bumping block H in contact with the peripheral face of the massive fly wheel G and its percussion lug or tappet G', the following arrangement is made: On 70 the bumping block H is secured an eye J connected by a wire, rope or other suitable flexible connection J' with an eye J² forming part of a spring device K which may be either in the form shown in Figs. 1 and 3 75 or in the form shown in Fig. 4. The spring device K shown in Figs. 1 and 3 consists of a spring board K' to the free end of which is secured the eye J², and the said spring board K' is fastened by a bolt K² 80 to a timber K³ attached to the under side of an overhead support K⁴ such as a ceiling or the like. The spring board K' is engaged by an adjusting screw K⁵ for regulating the tension of the spring board K'. In the 85 modified form shown in Fig. 4 the eye J² is mounted to slide in a bearing K⁶ held on a board K⁷ attached to the overhead support K⁴, and the upper end of the eye J² is pressed on by a spring K⁸ so as to yieldingly support the eye J². By adjusting the nut K⁹ at the top end of the eye J² the 90 tension of the spring K⁸ can be regulated. By reference to Fig. 1, it will be noticed that the flexible connection J' extends upwardly and slightly forwardly relatively to the pan A so that the bumping block H is 95 held in contact with the peripheral face of the massive fly wheel G and its percussion lug or tappet G'.

100

The tail end of the pan A is provided with an eye L connected with the lower end of a retention device in the form of a wire rope L' connected at its upper end to an eye L² spring-supported on a board L³ secured to the overhead support K⁴ previously mentioned.

105

In practice, the massive fly wheel G is of large diameter (3 to 4 feet) and the tappet or lug G' is comparatively diminutive, say, 110 half an inch as the maximum. The massive fly wheel G is driven at a high speed to de-

rive the mechanical effect of mass and velocity. A massive fly wheel G of four feet in diameter at a speed of 150 r. p. m. has a peripheral velocity of 1,875 feet per minute or 61 feet per second. If the lug or tappet G' has an angle of 30° then the horizontal throw of the pan would be near 30 feet per second. The massive fly wheel G has one or more complete revolutions to each impact, so no matter what the speed of the wheel may be the pan A may be adjusted at any given amplitude and periodicity, so many bumps per minute. If the pan A is bumping say 60 per minute and the lug or tappet strikes at each revolution, then the massive fly wheel G may be speeded up to 120 r. p. m. and still the pan be bumping at the same rate, namely, 60. The massive fly wheel G may be speeded up to 180 r. p. m. with the lug or tappet G' striking only every third revolution. In this manner any intensity of force may be figured on. If two or more lugs or tappets G' are used on the peripheral face of the massive fly wheel G then a wide variation of impacts may be arranged to suit any possible case, it being understood that the force of the impacts increases as the square of velocity of the massive fly wheel G. As shown in Fig. 5, two pans A are arranged on opposite sides of the massive fly wheel G and two percussion lugs G' are arranged on the peripheral face of the fly wheel G diametrically opposite each other. The two flexible connections J' of the two pans A connect with the eye J² of the spring board K', the eye J² being located directly above the center of the fly wheel G. The detail construction of the pan A may be varied according to the use made of the device. The pan A shown in Figs. 1 and 2 is provided with a series of transversely-extending perforate riffles P mounted to swing up and down in the pan A. The riffles extend in a forward direction. The operation is as follows: When the shaft F is rotated then the centrifugal inertia of the massive fly wheel G together with the percussion lug or tappet G' affords the necessary impact on the bumping block H to lurch the pan A to the right with such force and amplitude as is in keeping, first, with the weight of the loaded pan A, second, with the tension of the spring device K, and, third, with the radial inclination of the legs B², B³. When the legs B², B³ stand erect most of the weight of the loaded pan A is borne by them, particularly the hind legs B³. Much of the weight is held by the spring device K. When the pan A recoils from the impact given it as above described, it is by restraint held to the combined movement of the hinged legs B² and B³. When the pan is describing this path the spring device K is increasing in tension or lifting

effect, while the inclined legs are diminishing their sustaining effect. The tension of the spring device K is gaged in general to withstand the burden of weight and inertia that is brought to bear upon it throughout so that it may permit of any desired amplitude of the pan A under any given structural conditions and any given velocity of reciprocation. Thus, for instance, if the massive fly wheel G should have a speed say of 120 revolutions per minute, as above mentioned, then the pan A should recoil say about 6 inches and return in time to just meet the percussion lug G' at the next revolution of the wheel G, so that the total impact is the sum of the arrested motion of the pan A and the centrifugal impact of the percussion lug G'. The tension of the spring device K may be connected so that the impact shall be every other revolution of the percussion lug or tappet G' so that the pan A receives 60 bumps per minute instead of 120. From the foregoing it will be noticed that any desired effect may be reached by the adjustment of one or more of the constructive parts, that is, the legs B², B³ as to their length and inclination, the total weight of the pan and load, the inclination of the flexible connection J', the weight and speed of the massive fly wheel G, the thickness of the percussion lug G', etc., all of which should be in keeping with the needs of the case whether the apparatus is used for coal washing (coarse or fine) or for washing ore having baser metal or precious metals.

The reciprocating movement of the pan A due to the joint action of the spring device K and its flexible connection J' with the pan A and the legs B², B³ is very peculiar and very effective, as will presently appear. The spring device in the present case is designed to act in conjunction with the legs B², B³, the same as a toggle joint movement intervening between the power and the work, and is to hold the total weight, first, against the variable component of gravity, and, second, as against inertia of impact. At the instant following the impact, the pan A has its maximum velocity which is then retarded by the pull of the spring device K, but the normal effective force of the spring device is counteracted in a great degree by the increasing component of gravity of the load to that extent at times that the pan A settles back on its inclining legs B², B³, not being able to rise at all even though the spring device be at its maximum tension at the time. In this event the tension of the spring device is increased so that the periodicity and amplitude shall be correct for the given purpose. In the ordinary spring device now generally used the action and reaction are equal and opposed; that is to say, the recoil of the spring has the same vi-

lence as the impact of the percussion lug. This violent return jerk has a tendency to unseat the bed and all would flow toward the tail of the pan and there would be only a 5 shaking table like that of a screen; furthermore, there would be only a shuffling to and fro but no carrying effect toward the head would be produced. In the present cooperative mechanical movement the pan A near- 10 ing the terminus of the stroke backward is exceedingly slow both going and coming, and there is a well-gaged accelerated movement as the knuckle of the toggle joint straightens up and the spring device has its 15 full unrestrained effect.

It will be understood that the force of the impact is not spent upon the wheel G as if the latter were at a standstill, but it is the centrifugal inertia of the wheel that 20 takes the impact, and that force increases with the square of the velocity. Again, with the double action pans A, A shown in Fig. 5, the impacts are at the same instant and are counteractive. That they may be 25 constrained to bump at the same instant, the one spring device and the one connection operate both pans A, A, all other conditions being symmetrical.

From the foregoing it will be seen that 30 the return stroke at the instant of the impact is at its maximum speed and in a direction nearly horizontal, the legs being nearly vertical. The percussion lug or tappet G' strikes the bumper H at a high speed of the 35 massive fly wheel G. It is not as a sluggish push like that of a cam but more like that of a steam hammer and giving an instantaneous rebound as much so as the striking of two elastic balls that do not slide apart 40 but rebound with the reaction due to their elasticity. It will be noticed that the combination of this massive fly wheel G, hinged legs B², B³ and the force and direction of the spring power device K enable the widely 45 variable results and the much-needed possibilities required in successful coal washing and ore concentration. At the instant of impact the acceleration is greatest and the movement is horizontal, tending downwardly, which effects a reverse or upward and forward buoyancy to the bed, including the swinging riffles and interstitial mass. This forcible effect cannot be brought out by 50 merely bumping the pan against a fixed post or equivalent, since to get such an effect in a right degree necessitates a powerful positive mechanical movement actuating the pan to give it the necessary impetus.

Having thus described my invention, I 60 claim as new and desire to secure by Letters Patent:

1. The combination with a percussion

table having a percussion head, of an actuating device comprising a massive revoluble wheel having a percussion tappet of diminutive throw, and of high kinetic energy, actuating said percussion table, the said table being of such reduced proportions of mass relatively to the wheel, that the recoil of the impact shall not disturb the stability of the 70 wheel in its bearings or cause it to falter.

2. In a machine of the class described, a pan having an impact head at its forward end, a massive revoluble fly wheel provided on its peripheral face with a percussion 75 tappet coacting with the impact head of the pan, means for mounting the pan whereby the pan has a rearward and downward movement under the force of the impact, and a tension device having a flexible connection 80 with the forward end of the pan and adapted to exert an upward and forward pull on the said pan.

3. In an impact jig-pan of the class described, a pan, freely swinging riffles, legs 85 pivoted to the front and rear ends of the pan, the hindmost leg being radially shorter and thus describing a larger angular amplitude, rearward and downward, a resistant massive fly wheel with tappet impinging the 90 returning head of the pan, and tension means connected in inclined relation to the pan and adapted to counterbalance the downward component of motion and to return the pan into the path of the tappet. 95

4. In a machine of the class described, the combination with a pan mounted for rearward and downward movement, a massive revoluble fly wheel provided on its peripheral face with a percussion tappet adapted 100 to engage one end of the said pan, and a spring device connected with the said pan adapted to draw the latter toward the peripheral face of the said fly wheel and to exert an upward and a forward pull on 105 the said pan.

5. The combination with a percussion table mounted to oscillate and having a percussive head, of a massive revoluble wheel of large diameter provided on its peripheral 110 face with an integral percussion tappet adapted to engage the percussive head of said table to impart instantaneous rebound to said table, and tension means connected with the percussion table and adapted to return the latter into the path of the tappet. 115

In testimony whereof I have signed my name to this specification in the presence of two subscribing witnesses.
